UNITED STATES PATENT OFFICE

HARRY C. ZIMMERMAN, OF WASHINGTON, DISTRICT OF COLUMBIA

GUN MOUNT

Application filed April 20, 1929. Serial No. 356,725.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 The subject of this invention is a gun mount.

In the mounting of guns the positioning of the trunnions as low as possible to secure stability and as far to the rear as possible 10 to permit high angle firing with maximum ground clearance results in a disposition of the training mechanisms and the sighting appurtenances which is not conducive to the usual overhead arrangement of the equilibra- 15 tors.

The gun mount of the present invention is characterized by a simple equilibrating mechanism which is positioned directly underneath the cradle in such a manner that the effective length of the lever arm is increased 20 upon reduction of the pressure.

With the foregoing and other objects in view, the invention resides in the novel arrangement and combination of parts and 25 the details of construction hereinafter described and claimed, it being understood that changes in the precise embodiment of the invention herein disclosed may be made within the scope of what is claimed without de- 30 parting from the spirit of the invention.

A practical embodiment of the invention is illustrated in the accompanying drawings, wherein:

Fig. 1 is a view in side elevation, parts being shown in section of the improved gun mount in position of zero elevation;

Fig. 2 is a view in side elevation showing the disposition of the equilibrator with the gun in maximum elevation;

40 Fig. 3 is an enlarged view, partly in longitudinal section of the equilibrator.

Fig. 4 is a sectional view on the line 3—3 of Fig. 4.

45 Referring to the drawings by numerals of reference:

The mount comprises a carriage including wheels 5, axle 6, split trails 7 and under-carriage 8 in which is a pintle 9, pivoting a top carriage 10. A cradle 11 mounting a re- 50 ciprocable gun barrel 12 is trunnioned at 13

in the top carriage at a point which is a considerable distance to the rear of the center of gravity of the tipping parts and only a slight distance above the horizontal plane passing through the axle so that the gun possesses as 55 low mounting as practicable. The elevating mechanism for the cradle consists of a segmental gear 14 engageable by a pinion 15 on a shaft 16 extending transversely of the cradle.

The equilibrating mechanism is arranged underneath the rear portion of the cradle and comprises a plunger rod 17 pivoted to the rear extremity of the cradle and working in a guide frame 18 pivoted at 18a to a relatively 60 fixed part of the mount, in the present instance the top carriage 10, at a point forwardly of the trunnions and directly in rear of the axle. The guide frame 18 consists of three 65 equidistantly spaced rods 19 connected to the bearing block 20 by nuts 21 and at their free end carrying a spring seat 22 confined by nuts 23.

The plunger rod which passes through an aperture 24 in the seat 22 likewise carries a 70 spring seat 25 which is slidable on the guide rods. Compression springs 26—26 embracing the plunger rod and confined between the 75 seats 22 and 25 normally tend to telescope the units of the equilibrator and counter-balance 80 the tipping parts.

When the gun is moved to its position of maximum elevation, as seen in Fig. 2, the springs will be extended and the spring seat 85 25 carried by the plunger rod 17 will be arrested by the bearing block 20. The point of attachment of the equilibrator to the fixed part of the mount is selected with relation to the trunnions to provide a gradually increasing lever arm so that the moment of the tipping parts upon elevation will be balanced 90 by the moment of the equilibrator.

I claim:

1. In a gun mount a wheeled axle unit, a 95 top carriage carried thereby, a cradle trunnioned in the top carriage in rear of its center of gravity, an equilibrator connected to the rear extremity of the cradle and to the top carriage below the cradle, and substan- 100

tially in the horizontal plane through the axle.

2. In a gun mount a support rotatable on a vertical axis, a cradle trunnioned therein in rear of its center of gravity, an equilibrator connected to the cradle in rear of the trunnions and to the support forwardly of and below the trunnions and the point of attachment to the support being in rear of the vertical axis of the support.

HARRY C. ZIMMERMAN.
